UNITED STATES PATENT OFFICE.

CLARENCE H. STRAIGHT, OF BRYAN, OHIO.

TWO-WHEELED VEHICLE.

SPECIFICATION forming part of Letters Patent No. 276,500, dated April 24, 1883.

Application filed February 10, 1883. (No model.)

To all whom it may concern:

Be it known that I, CLARENCE H. STRAIGHT, a citizen of the United States, resident at Bryan, in the county of Williams and State of Ohio, have invented certain new and useful Improvements in Road - Carts; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a vertical sectional view of my cart. Fig. 2 is a top view; and Figs. 3, 4, and 5 are detail views.

This invention has relation to road - carts; and it consists in the construction and novel arrangement of devices, as hereinafter set forth, and pointed out in the appended claims.

In the accompanying drawings, the letter *s* designates the axle, and *d* the side bars connected thereto. The shafts *e* are formed with downwardly-curved rear ends, which are firmly mortised into said side bars, and are braced at the joint by means of angle-irons *b*. Each side bar is formed with a forward extension, *t*, which is connected by brace-rod *a* to the shaft *e*, in front of its rear bend. The shafts are connected by a cross-bar, *c*.

The body *B* of the vehicle is supported by springs in front, connected to the cross-bar of the shafts or to the side bars, and in rear by springs *l* and joint-braces *j* and *k*, the upper ends of which are pivoted to shackles *g*, on which the body rests.

To the upper and rear end of the spring *l* is attached a block or bearing, *i*, to which the lower ends of the joint - rods *j* and *k* are connected, the former being pivoted to a shackle, *h*, on said block. The spring-blocks are connected by the tie-brace *y*. The brace-rods *j* extend forward and upward obliquely from the bearing *i* to the shackle *g*, and bear the weight of the rear portion of the body, transferring it to the springs *l* through the spring block or bearing *i*. The stay-rod *k*, in rear of the brace-rod *j*, is also pivoted to the shackle *g*. The stay-rod is designed to work in connection with the brace-rod *j* and the front spring or connection, *o*. Its office is to prevent the rear por-

tion of the body from swinging downward in a circular manner, as it keeps the rear spring extended and secures parallelism in the motions of the body and spring-block. The lower end of the stay-rod *k* is threaded, and passes through an enlarged aperture in the spring-block, and also through an opening or slot in the upwardly-bent rear end of the sprung-block *l*, or bearing at the rear end of the spring-block, and receives a pivot - bearing, *n*, and a nut, *p*. By tightening or loosening the nut *p* the rear of the body can be raised or lowered to suit the height of the horse or the weight of the burden. The spring *l* is connected at its lower end to a shackle, *q*, and clip *r*, whereby it is attached to the axle. This spring extends obliquely backward and upward, supporting the sprung-block. At its rear end is formed a boxing or bearing, *m*, for the pivot - piece *n*, through which the stay-rod passes. The fulcrum-pivot *n* permits a vibratory movement of the stay-rod, preventing it from being injured. The play of the stay-rod at its lower end is also necessary to secure the full benefit of the action of the spring *l*.

The front connection or spring, *o*, may be made in elongated and curved form, and may be connected to the cross-bar *c* by means of a shackle and clip. In addition to its function in supporting the front of the body, it is designed to assist the stay-rod *k* in preventing the downward tendency of the rear of the body and the swinging of the rear springs in a radial manner around the axle.

The transverse equalizing-connection *y* is designed to resist side action of the springs, and holds them in position.

When the forward springs are designed to be connected to the side bars they are made in edge-curved or horseshoe form, as indicated at *o'*, the spring having also a vertical curvature or upward arch from its outer end, which bears on or is connected to the side bar, to its inner end, which is connected to the sill of the body. Usually the outer and lower end of this spring is pivoted to a shackle which is clipped to the side bar. This spring is designed not only to have the ordinary upward elasticity, but also a torsional elasticity, which renders it of especial fitness for co-operating with the stay-rod *k* in resisting the downward tendency of the

rear end of the body while supporting its front end.

A horseshoe - shaped torsion - spring is not broadly claimed herein.

Having described this invention, what I claim, and desire to secure by Letters Patent, is—

1. The combination, with the axle and side bars, of the rear springs extending obliquely upward and backward, the spring-blocks connected thereto, and the pivoted brace-rods and adjustable stay-rods engaging bearings of the spring-block, substantially as specified.

2. The combination, with the axle and side bars, of the rear springs, extending obliquely backward and upward from the axle, the spring-blocks, brace-rods, stay-rods, and front springs or connections, substantially as specified.

3. The combination, with the axle, shafts, and side bars having braced connections to said shafts, of the oblique rear springs, supporting brace-rods and stay-rods extending to the rear portion of the body, the transverse equalizing - connection *y*, and the front springs or connections supporting the front of the body, substantially as specified.

4. In a road - cart, the combination, with oblique rearwardly-extending rear springs, supporting pivoted brace-rods extending upward to the body, of the adjustable stay-rods in rear 30 of the brace - rods, and edge - curved torsion-springs supporting the front portion of the body and connected to the side bars, substantially as specified.

5. The oblique rear spring having a shackle-bearing at its lower front end and a box-bearing at its upper rear end for a fulerum-piece on the stay-rod, substantially as specified.

6. The combination, with the rear spring, of the spring-block, the shackles *g* and *h*, the pivoted brace-rod, the adjustable stay-rod having its lower end threaded, the pivot-piece through which the stay-rod passes, and the nut engaging its end, substantially as specified.

In testimony whereof I affix my signature in 45 presence of two witnesses.

CLARENCE H. STRAIGHT.
